M. BUCHHOLZ

CONTROL OF ELECTRIC APPARATUS

Original Filed Sept. 15, 1922

Inventor:
Max Buchholz

by

Atty.

UNITED STATES PATENT OFFICE.

MAX BUCHHOLZ, OF CASSEL, GERMANY.

CONTROL OF ELECTRIC APPARATUS.

Original application filed September 15, 1922, Serial No. 588,457, and in Germany January 21, 1922.
 Divided and this application filed April 16, 1925. Serial No. 23,678

My invention has reference to a method and means for protecting electric apparatus operating in an insulating liquid, such as oil transformers, oil switches, grounding 5 throttling coils, resistances and the like, and it is one of the important objects of my invention to provide a device of very simple construction and great reliability, and adapted to operate before extensive injuries to the 10 apparatus to be protected can occur by sparking, overloading or other disturbances.

My invention is particularly based on the fact that in the case of disturbances in the operation of the apparatus to be protected 15 or in the case of sparking or other irregularities of operation, or whenever such irregularities are imminent, as well as in the case of any ebullition or fermentation processes in the oil, serving as an insulating liquid, 20 bubbles of gases of decomposition are formed which can operate a protective means, for instance an electric contact, either a working or a closed contact, which is adapted to switch out of circuit the apparatus to be protected, or which will operate an alarm or 25 annunciator device indicating the disturbance, or which is adapted to effect both kinds of operations. The gases formed by decomposition may influence the protective means 30 in different ways, this application being a division of my copending application Serial Number 588,457 filed September 15, 1922.

I may for instance utilize a displacement of the insulating liquid occurring in consequence of the unnormal conditions of working mentioned above to vary the operative 35 conditions of the protective circuit.

A protective device embodying this invention is illustrated in the drawings annexed 40 to this specification by way of example in a purely diagrammatic manner.

The drawing shows the elevation of an oil insulated transformer with an overflow pipe for the oil and a balance beam acting as a 45 switch for the opening and closing of the protective circuit.

In the drawing *a* is a transformer casing, *b* is the core of the transformer, *c* are the windings, *d* are the leading-in insulations 50 for the conductors, *e* is an oil switch with a releasing coil *f* and *g* is a source of current which, upon the operation of the safety device, excites the coil, opens the oil switch and causes the switching-out of the apparatus. 55 *o* is an overflow pipe mounted in the cover

of the vessel *a* and *n* is an expansion vessel in communication with this pipe. *v* is a cup disposed below the upper end of the overflow at one end of a balance beam *u* pivoted on an axle *w* and having a contact piece *k* attached 60 to its other end. The protective circuit comprising the source of current *g* and the coil *f* is connected with the axle *w* and can be closed or opened by the contact piece *k*. The core *z* of the coil is influenced by a coil 65 spring *x* and serves to retain a short circuiting device *y* in inoperative position. The device *y*, on being allowed to drop, will establish a short circuit whereby the fuses *t*, *t* will be destroyed and thereby cut out the 70 transformer. Any gases of decomposition formed in the vessel *a* will cause oil to be expelled through the overflow tube *o*, thereby ejecting small quantities of oil from the free end of the tube. The ejected oil, in 75 dropping into the cup *v*, will by its weight cause the contact *k* to be opened whereupon the core *z* will be withdrawn by the spring *x*, thereby releasing the short circuiting device *y* and thus cutting out the transformer. 80

The circuit to be controlled by the contacts referred to may excite either directly or by the medium of an intermediate relay the releasing coil of an oil switch which interrupts the endangered circuit. In the case of 85 apparatus the circuit of which does not include an oil switch, as frequently occurs, for instance in the cases of transformers mounted in the field at wide distances apart, other provisions should be made for the purposes 90 of this invention.

Besides the form of construction herein shown and described, the invention is susceptible of a variety of other modifications and forms of application of the principle of 95 my invention all of which operates substantially in a similar manner. The means of connecting the contacting device with the releasing circuit and the switching means are open to changes and alterations without any material importance for the operation 100 of the apparatus according to my invention which in its broad aspects comprises the operation of safety devices for electric apparatus or the like, adapted for operation by vapors, fumes, gases or similar emanations liberated and expelled from the insulating medium, and means adapted to be operatively influenced by such emanations, and 105 connected to fuses or equivalent safety 110

means, the instrumentalities shown and described in this specification as embodiments of these principles being susceptible of modifications without deviating from the spirit 5 of my invention as set forth in the claims.

In the claims the term "gases" is meant to comprise also vapors and fumes.

I claim:—

1. The method of controlling unnormal 10 working conditions of liquid-insulated electric apparatus, comprising causing an expulsion of insulating liquid occurring in consequence of such a decomposition of such liquid and causing such expulsion to vary the 15 operative conditions of a protective circuit.

2. Protective system for liquid-insulated 20 electric apparatus comprising a container and a supply of insulating liquid surrounding the apparatus to be protected, a protective circuit and means adapted to be operated by an expulsion of insulating liquid occurring in consequence of a decomposition of such liquid for varying the operative conditions of said circuit.

25 3. Protective system for liquid-insulated electric apparatus comprising a closed container for said apparatus, a supply of insulating liquid in said container surround-

ing said apparatus and adapted to completely fill said container, a protective circuit, an overflow tube on said container and a contact device operatively related to said tube and adapted to be actuated by insulating liquid escaping from said tube. 30

4. Protective system for liquid-insulated 35 electric apparatus comprising a closed container for said apparatus, a supply of insulating liquid in said container surrounding said apparatus and adapted to completely fill said container, a protective circuit, an overflow tube on said container, a double armed contact lever and a cup on said lever below the free end of said overflow tube and adapted to be actuated by insulating liquid escaping from said tube. 40

5. Protective system for liquid insulated 45 electric apparatus comprising a container and a supply of insulating liquid surrounding the apparatus to be protected, a protective means adapted to be operated by an 50 expulsion of insulating liquid occurring in consequence of a decomposition of such liquid for varying the operative conditions of said protective means.

In testimony whereof I affix my signature.
MAX BUCHHOLZ.
